US00D941398S

(12) **United States Design Patent** (10) **Patent No.:** **US D941,398 S**
(45) **Date of Patent:** **** Jan. 18, 2022**

(54) **POP IT FIDGET TOY**

(71) Applicant: **SHENZHEN HUWANG SILICONE RUBBER PRODUCTS CO., LTD,**
Shenzhen (CN)

(72) Inventor: **Haisheng Zhang**, Hefei (CN)

(73) Assignee: **SHENZHEN HUWANG SILICONE RUBBER PRODUCTS CO., LTD,**
Shenzhen (CN)

(**) Term: **15 Years**

(21) Appl. No.: **29/776,528**

(22) Filed: **Mar. 30, 2021**

(51) LOC (13) Cl. **21-01**

(52) U.S. Cl.

(57) **CLAIM**

The ornamental design for a pop it fidget toy, as shown and described.

DESCRIPTION

FIG. 1 is a front perspective view of a pop it fidget toy showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.
